INVENTOR.
EDWARD P. LANGWORTHY
BY *H. G. Palmer*
ATTORNEY.

UNITED STATES PATENT OFFICE.

EDWARD P. LANGWORTHY, OF BUFFALO, NEW YORK, ASSIGNOR TO AMERICAN RADIATOR COMPANY, OF CHICAGO, ILLINOIS, A CORPORATION OF NEW JERSEY.

MOLD-MATERIAL-PROJECTING MACHINE.

Application filed June 15, 1920. Serial No. 389,101.

To all whom it may concern:

Be it known that I, EDWARD P. LANGWORTHY, a citizen of the United States, residing at Buffalo, in the county of Erie and State of New York, have invented certain new and useful Improvements in Mold-Material-Projecting Machines, of which the following is a full, clear, concise, and exact description, reference being had to the accompanying drawings, forming a part of this specification.

My invention relates to improvements in devices for projecting mold material into molds.

One of the objects of my invention is to provide an apparatus for projecting the mold material into molds in the form of small compact wads projected at a high velocity whereby the sand will be properly packed into the mold.

Another object of my invention is to provide an apparatus of the above character which will project the sand with the least spreading or throwing of loose sand and which will require the minimum power for operation.

For the purpose of disclosing my invention I have illustrated one embodiment thereof in the accompanying drawings in which:

Fig. 1 is an elevation showing my machine in operative position.

Fig. 2 is a sectional view taken on the line 2-2 of Fig. 1.

Fig. 3 is a plan view of the machine.

Fig. 4 is a transverse sectional view of the rotary projector.

Fig. 5 is a side elevation with the cover portion broken away to show the construction of the rotor; and

Fig. 6 is a perspective view of one of the blades.

In the embodiment illustrated, I provide a mast or support 1 which may be suitably braced as by braces 2. At the top of this mast there is an I-beam 3 having at its rear end bolted thereto a pair of arms 4 which in turn are secured to a bifurcated support 5 extending from a sleeve 6 pivotally mounted on the post 1. At the forward end of the I-beam 3 there is likewise provided a bifurcated extension 7. Between the ends of the extension 7 there is mounted a pulley or roller 8 and the joint between the arms 4 and 5 is preferably formed by the shaft 9 of a second roller 10. A belt conveyor 11 is mounted on these pulleys and the top of the belt conveyor preferably forms the bottom of a trough formed by a pair of side members 12 secured by suitable braces or supports 13 to the I-beam. These side members project above the belt or conveyor so that the contents thereof will not be spilled off on the side. The forward end of the arm is held in horizontal position by means of suitable braces 14 which are preferably connected to the bifurcated arms 7 at the point where the pulley 8 is journaled. The arm 3, due to its sleeve connection with the mast, may be swung in a horizontal plane, the braces 14 being secured to a rotating sleeve 14^a to permit the entire structure to swing.

At the outer end of the arm 3 is mounted a depending link member 16 from which depends a swinging frame. This frame preferably consists, as shown, of a vertical arm 17 and horizontal platform 18. An electric motor 19 is secured on the platform and the top of the motor frame is secured by a universal coupling 20, to the link 16. At the lower end of the arm 17 is mounted a rotary projector for the mold material. As illustrated, particularly in Figs. 4 and 5, this projector comprises a dished wheel 21 mounted on a shaft 22, journaled in the lower end of the arm 17. A belt 23, passing over a pulley 24 on the shaft 22 and a pulley 25 on the shaft of the motor 19 serves to drive the projector in a counter clock-wise direction with the parts in position as illustrated in Fig. 5. The periphery of the wheel is formed with a straight portion 26 and at suitable intervals on the inner face of the wheel are formed a series of radial ribs 27 which are obliquely disposed and which preferably increase in width toward the periphery of the wheel. Transversely extending from the straight portion 26 of the wheel, are a series of radial obliquely disposed paddles or blades 28 which are provided at their rear or secured end with an angularly disposed flange 29 through which bolts

30 may pass to secure these blades in position upon the flange 26. A stationary cover 31 encloses the periphery of the wheel and this cover is provided with sides 32 and 33 which extend partially down on each side of the wheel substantially the height of the paddles so that that portion of the wheel is snugly and completely enclosed. This casing is preferably made in two sections to 10 permit its being assembled on the wheel and is secured to the arm 17 by means of suitable braces 34. This casing, as is shown in Fig. 5, is open at 35 and tangentially with the wheel, the cover is extended to form vertical walls 36 and 37, providing a spout through 15 which the mold material may be projected.

Secured over the front face of the casing is a cover plate 38 which together with the casing encloses the wheel. This cover plate 20 38 is provided with an aperture 39 through which projects the lower end of a chute 40, the upper end of which is immediately below the outer end of the conveyor belt 11 to receive the material therefrom. This chute is 25 secured in position by any suitable brace, as for instance, a brace 41, on the horizontal arm 17. It is thus seen that the chute and head are so mounted that the lower end of the chute moves in whichever direction the 30 projector moves and that the projector, due to the universal joint 20 may be swung to any position to direct the material into different parts of the mold. Furthermore, due to the fact that the arm 3 is pivoted at 6, 35 this arm can also be swung to permit a wider range of movement if desired.

In operation the material is deposited on the rear end of the traveling belt 11 by any suitable apparatus, such, for instance, as a 40 chute leading from a hopper or a chute leading from a conveyor, or in any other desired manner. The material is preferably fed at a definite rate and is carried forward by the conveyor and deposited into the chute 40 by 45 which it is conveyed to the rotating projector and delivered to the projector substantially at the center of the dished wheel, therefore the stream or column of sand is not struck as hard a blow by the blades or 50 ribs 27 as it would be if it were fed transversely to the blades 28. The sand being fed at or near the center of the rotary projecting wheel is picked up and by centrifugal force 55 thrown outwardly toward the casing 31, the ribs 27 aiding in this operation although even if the ribs 27 are left out, the friction of the side of the wheel would have the same tendency to throw the sand out toward the 60 periphery of the wheel. As the sand is projected by centrifugal force toward the periphery of the wheel, it is also carried around at the periphery by the paddles 28, being held from further centrifugal projection 65 by the casing 31 and compacted into wads against the paddles or blades and the

casing being finally projected downwardly through this opening 35.

Having thus described my invention, what I claim as new and desire to obtain by Letters Patent is:

1. A molding machine comprising a support, a rotary member mounted thereon having a recessed central portion and a horizontally - projecting peripheral flange portion extending therefrom, tapering radially-disposed blades in said recessed central portion and curved blades fixed upon said horizontal portion adjacent to the outer ends of said tapering blades, a casing enclosing said rotary member and provided with a central inlet, means for delivering mold material to said inlet; said casing having an outlet, and means for actuating said rotary member to project the mold material through said outlet, substantially as specified. 70 75 80 85

2. A molding machine comprising a support, a rotary member mounted thereon having a recessed central portion and a horizontally - projecting peripheral flange portion extending therefrom, tapering radially-disposed blades in said recessed central portion having their wider ends extending out of said recessed portion, and curved blades fixed upon said horizontal portion adjacent to the outer projecting ends of said tapering blades, a casing enclosing said rotary member and provided with a centrally disposed inlet, a chute having one end extending into said centrally disposed inlet opening for delivering mold material centrally to said rotary member, said casing having a tangential outlet, and means for actuating said rotary member to project the mold material outwardly through the outlet in said casing, substantially as specified. 90 95 100 105

3. In a molding machine the combination with a rotary disk having a radial rib on one face thereof and a transversely projecting blade near its periphery, of a stationary arcuate casing wall peripherally disposed about said disk and means for delivering mold material to said disk at substantially its center. 110

4. In a molding machine the combination with a vertically extending support, a horizontally disposed arm mounted on said support, a molding material projector comprising a rotary disk secured at the outer end of said arm and having a universal connection with said arm to permit the same to swing in any direction, and a chute movable with said disk, delivering molding material to said disk at substantially its center. 115 120 125

5. In a molding machine, in combination with a stationary support, of a horizontally disposed arm extending therefrom, a rotary molding material projecting support depending from the outer end of said arm having a rotary molding material projector at its lower end comprising a casing, a rotary 130

member therein, centrally disposed tapering blades on said rotary member, and curved peripherally disposed blades on said rotary member arranged adjacent to the ends of

at the point where the support is joined to the arm, and means for connecting said motor with said projector for operating the 10 same.

8 said centrally disposed blades, a motor for driving said projector mounted on said support above said projector, and substantially

In witness whereof, I have hereunto subscribed my name.

EDWARD P. LANGWORTHY.
